GASKET CUTTER

Carl B. Kromsten, Brooklyn, N. Y.

Application July 14, 1955, Serial No. 36,977

Term of patent 14 years

(Cl. D54—13)

Fig. 1

Fig. 2

Fig. 3

Fig. 4

Figure 1 is a top perspective view of a gasket cutter showing my new design;

Figure 2 is a bottom perspective view thereof showing the side opposite that shown in Figure 1;

Figure 3 is a top plan view thereof; and

Figure 4 is a cross-sectional view of the same taken along the line 4—4 of Figure 3 looking in the direction of the arrows.

The dominant features of my new design are shown in solid lines.

I claim:

The ornamental design for a gasket cutter, as shown and described.
